UNITED STATES PATENT OFFICE.

FRANCIS C. OSBORN, OF DETROIT, MICHIGAN, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CHANGE MAKING, INDICATING, AND REGISTERING MACHINE.

No. 864,185.

Specification of Letters Patent.

Patented Aug. 27, 1907.

Application filed December 10, 1891. Serial No. 414,612.

To all whom it may concern:

Be it known that I, FRANCIS C. OSBORN, a citizen of the United States, residing at Detroit, in the county of Wayne and State of Michigan, have invented certain new and useful Improvements in Change Making, Indicating, and Registering Machines, of which the following is a specification.

This invention relates to an automatic change making mechanism, and has among its principal objects to provide a machine which will automatically compute or predetermine the amount of change to be delivered when a certain amount of money is paid in to cover a purchase of a certain amount. That is, manipulative means, such as keys, are provided which may be operated by the clerk or operator according to the amount deposited or paid in and also according to the amount of purchase, with coöperating mechanism whereby the machine itself automatically computes or controls the ejection of the proper change to be delivered equivalent to the difference between the amount paid in and the amount of purchase. This mechanism therefore entirely dispenses with any mental calculation in making change and insures absolute accuracy.

Another object is to combine the above change-making mechanism with a cash register and indicator, whereby the machine shall register, and if desired also indicate, the amount of the purchase or sale as well as control the ejection of the proper amount of change; and still further to combine therewith a change indicating device to indicate to the customer or the clerk the amount of change to be returned. Of course the change-maker may be used separately, or combined with the cash register and indicator, with or without the change indicator.

A further object is to construct this automatic change making mechanism in such manner that it will have change controlling or selecting devices with means for controlling the said devices in two opposite senses, thereby placing the selecting mechanism in condition to determine the amount of change to be indicated or ejected.

Another object is to construct the change indicating device in such manner that it may also serve as a selecting or controlling mechanism for the change delivering devices, having separate parts independently adjustable for purchase and deposit amounts successively, the final position of the indicator determining the amount of change to be delivered.

A further object is to provide an ejecting or delivering mechanism adjustable to deliver different desired numbers of coins or checks at a single operation, together with various other improvements in the money ejecting mechanism.

A further object is to provide a delivering mechanism normally inaccessible to the operator, with means for compelling a regular operation of the machine before access to the delivering mechanism may be had.

An additional object is to provide an improved device for compelling a complete operation of the mechanism, which may be termed a full-stroke device.

With these and incidental objects in view the invention consists in certain novel features of construction and combination of parts, the essential elements of which are set forth in appended claims and a preferred form of embodiment of which is hereinafter described with reference to the drawings which accompany and form part of this specification.

Of said drawings: Figure 1 shows a plan of the register and change indicating and change making mechanisms. Fig. 1^a is a detail view of the laterally shifting transfer rod. Figs. 2, 3 and 4 show details of mechanism connected with the change selecting devices, Fig. 5 is a vertical transverse section through the machine. Figs. 6 and 7 show details of the key board. Figs. 8, 9 and 10 show details of the change selecting mechanism. Fig. 11 shows the mechanism for controlling the selecting devices through the deposit mechanism. Fig. 12 shows the fixed cover of a coin receptacle. Fig. 13 is a development of the change selecting device showing the graduated projections for determining the amount of change. Fig. 14 is an elevation of the left hand end of the machine. Fig. 15 shows a flash for the indicators. Figs. 16, 17, 19, 20 and 21 are forms of boxes used to contain bills or gold coins. Fig. 18 shows an elevation of the left-hand end of the machine with parts in a different position from that shown in Fig. 14. Figs. 22 and 23 show the multiple ejecting mechanism. Figs. 24, 25 and 26 are details of the coin holders. Figs. 27 and 28 are elevations of the right-hand side of the machine, Fig. 28 showing most of the parts in normal position, and Fig. 27 showing them in partly operated position. Figs. 29 and 30 are details of the full-stroke mechanism. Fig. 31 shows a detail of the transfer devices for the selecting mechanism. Fig. 32 is a detail showing the locking means for the selecting mechanism. Fig. 33 is a perspective of the machine in the cabinet. Fig. 34 is a perspective of the machine with the cabinet removed.

The change making mechanism described herein is shown in combination with cash registering devices, which combination increases the field of usefulness of the latter, but clearly either the change indicating or the change making mechanism may be used separately without any cash register connection for keeping a continuous record of sales in the machine. The mechanism shown herein is adapted for use in many

existing types of cash register, but it is described herein in connection with a machine such as is shown in the patent to Osborn No. 455,111.

As a general description of the mechanisms devised for accomplishing the broad purposes above set forth, it may be stated that a selecting or change controlling mechanism is provided which is controlled by manipulative means, such as keys, according both to the amount of purchase and the amount deposited or paid in; and this selecting mechanism in turn controls the ejecting or delivery of the money or change. The said selecting or change controlling means is caused to assume a certain condition under the control of said manipulative means whereby to insure the ejection of the proper amount of change represented by the difference between the amount of deposit and the amount of purchase. The purchase and the deposit mechanisms are arranged to position the selecting mechanism in accordance with the value of said devices.

20 The ejecting devices are controlled as to their operation by the final position or condition of this adjustable change selecting mechanism to eject the proper change.

It will be understood that the term deposit mechanism is used to refer to that part of the machine which is controlled in accordance with the amount of money paid in by the customer, and the term purchase mechanism is used to mean that part of the machine controlled in accordance with the amount of the sale. With this understanding it may be said that the purchase mechanism in the present machine comprises a series of banks of keys, each bank serving to indicate numbers from 1 to 9 inclusive. The deposit mechanism comprises a series of slides covering the various coin tubes or receptacles whereby in order to insert any deposited coin in its proper receptacle it is necessary to withdraw the cover of the same. These covers are of course marked according to their denominational values, just as the purchase keys are marked, except that there are only covers for the particular values of subsidiary coins and bills, whereas the purchase keys are arranged in the ordinary banks in values from 1 to 9. It will be understood, however, that any other of the well known forms of manipulative means may be used for these deposit and purchase amount determining mechanisms without departing from the spirit of the invention.

In the present embodiment, the aforesaid change controlling mechanism comprises a series of denominational selecting devices controlled by the deposit and the purchase devices in opposite senses, the final position of these denominational selecting devices determining the amount of change to be delivered. These selecting devices are also used as change indicators, and in the form adopted herein, comprise revolvable drums or wheels, one drum for the units of cents denomination, another drum for the dimes denomination, another for the units of dollars denomination, and so on. These selecting or indicating devices normally stand in zero position, so that as indicators they show a row of zeros. Then under the control of the purchase mechanism or keys, these selecting or indicating devices are moved reversely to an extent dependent upon the amount of sale so that they thereby are set to positions showing a "complement" of the amount of sale, as will be more fully explained later. Then

the deposit devices effect the positioning of these selecting devices oppositely to their previous movement, and to an extent dependent upon the amount of deposit, so that the resultant position represents and determines the amount of change to be delivered. In order to properly position these selecting devices, transfer mechanisms have been devised for connecting the adjacent denominational members of said selecting devices, so that a movement of the selecting member of one denomination will produce a movement of the adjacent denominational selecting member, thereby insuring the proper resultant or final position of these selecting members under the control of both the deposit and the purchase mechanisms, as will be more fully explained hereinafter. After these change selecting devices are brought to their final positions, the ejection of the change from the machine is controlled and caused by the operation of the cover for the money tubes or receptacles. Normally the receptacles are inaccessible to the operator, and it is only when the machine as a whole is operated, that they are so accessible. When the said cover is moved, the money delivering mechanism is operated and the proper change ejected.

A detailed description of this machine divides itself into three main parts, namely, the purchase mechanism, the deposit mechanism and the mechanism for delivering change. If the machine is to be used as a sale register only the purchase mechanism is necessary, if as a change indicator, both the purchase and deposit mechanisms are required, which if change making is required the ejecting mechanism must be added to the purchase and deposit mechanisms. A detailed description of the parts will hereafter be given in the order named.

The purchase keys are best shown in Fig. 5 and are indicated by reference letter P. In the machine as shown there are four banks of these keys having numbers from 1 to 9 on their checks and they are adapted to be separately depressed. The purchase operation consists in depressing the proper keys P and in then moving the operating handle 39 and the operating lever 38 from the position of Fig. 14 to that of Fig. 18. The operating lever 38 is mounted rigidly on shaft 88 (Fig. 5) and serves to depress a yoke having radial arms y connected by a bar Y extending under and traversing the banks of keys. For each denomination a slide is provided having notches into which a series of pawls 1, 2, 3, and 4 mounted on and movable with yoke piece Y are adapted to engage. In the normal position of the keys they do not extend into the path of the said pawls but when any of the keys is depressed and the yoke lowered the proper pawl will during its movement strike the depressed key, and be cammed toward the right as shown in Fig. 1 into some one of the notches of slide s. During the remainder of the movement of the pawl it will clearly serve to carry the slide s with it, thereby a differential motion of the slides s is obtained.

The purchase indicating mechanism is similar to that shown in the patent referred to and is operated through the chains attached as shown in Figs. 1 and 5 to the tops of the slides s. Near the lower end of the said slides additional chains 8, 9, 10 and 11 are attached and these are connected to the change collecting mechanism, the chains being supported by rods r. The change select-

ing mechanism will be more fully described hereafter, but it will be seen that on Fig. 1 a series of wheels 15, 17, 19 and 21 are provided which have a series of numbers from 0 to 9 inclusive arranged consecutively on 5 their peripheries serving as a change indicator. Graduated projections are placed on the said wheels forming the change deliverer controlling mechanism.

It will be seen that the change indicating numbers on the wheels 15, 17, 19 and 21 increase in a counter 10 clockwise direction as the wheels are viewed in Fig. 5 so that the movement of the slides under control of the 15 pawls and yoke Y moves the change indicators reversely, from zero, then to 9, then to 8, etc., thereby bringing them to a position such that the difference between the amount exhibited by the purchase keys and 10,000 is indicated on the said wheels. For this reason the 20 wheels may be termed complement wheels.

It will be seen that if all the complement wheels are 25 in zero position as shown in Fig. 1, and any one of them is moved reversely, a movement of one step should occur in all the higher denominations of complement 30 wheels in order to give the proper complement. For example, if eight cents was registered as the purchase amount, the complement wheel 15 would be moved reversely from zero, then to 9, and so on for eight units until the number "2" was exhibited thereon; but, unless the higher denominations of complement wheels were reversely moved one step, this indication would be incorrect inasmuch as the indicator would show 35 0002 whereas it should show 9992. To perform this reverse transfer a series of fingers 5, 6 and 7 is provided mounted on the yoke piece Y as shown in Figs. 1, 2, 3 and 4. Figs. 2 and 3 show the mechanism from underneath, Fig. 2 being in normal position and Fig. 3 showing the parts in operated position. The pawl 1 is as 40 stated mounted on the yoke piece Y and is connected through a pin to a slide 14 also carried by the yoke piece which is shaped as shown in Fig. 2 so as to give movement in one direction to a second slide 13 though not in the reverse direction, said slide 13 producing a similar action on the third slide 12. Slide 14 is connected to finger 5 by a pin as shown, slide 13 is connected to finger 6 and slide 12 is connected to finger 7 also by pins. The pawls 2 and 3 are provided with 45 notches in which rest pins, the pin for pawl 2 being carried by slide 13 and the pin for pawl 3 by slide 12. The result of this construction is that if pawl 1 is operated by striking a depressed key it is moved from the position of Fig. 2 to the position of Fig. 3 and thereby 50 through its connection with slide 14 moves finger 5. Slides 13 and 14 and slides 12 and 13 being linked as shown, movement of pawl 1 will also produce movement of the two slides thereby rocking fingers 6 and 7 around their pivots but producing no motion of pawls 55 2, 3 or 4. If a key in the second bank from the right is depressed, pawl 2 will when yoke piece Y is drawn downward be moved to the right and through its notch and the pin on slide 13 will move the said slide and the slide 12 thereby carrying fingers 6 and 7 with it, but it will be clear that neither finger 5 nor pawl 1 will be moved owing to the lost motion link connection between slides 13 and 14. If pawl 3 is adjusted through the depression of a key in the third bank from the right, finger 7 will be also moved but not fingers 5 and 6 nor 60 pawls 1 and 2.

It will be seen that as a whole when any pawl is operated it produces no effect on the other pawls but does cause movement of the fingers relating to the higher denominations of amounts. This movement of the fingers to the position shown in Fig. 1 brings the lower 65 ends of said fingers so that their planes of movement intersect the chains 8, 9, 10 and 11 between the two rods r. When the yoke piece Y is given the last increment of its downward movement the pawls which have not been adjusted to the right will pass the 70 chains, those pawls which have been so adjusted will strike the chain and double the same between the two pins, thereby causing an additional increment of movement of the complement wheels. It will be evident that this mechanism performs precisely the transfer function required, that is, when any selecting device is moved reversely from its normal zero position, it causes a reverse movement equal in extent to one step in the selecting wheels of higher 75 denominations, independently of whether they are actuated by their own slides or not.

Details of the change selecting mechanism are shown in Figs. 8, 9 and 10. It has been assumed in the previous description that the chains were connected directly to the change indicating and selecting wheels 80 15, 17, 19 and 21 but this is not strictly the case. As shown in Fig. 8 each complement wheel is provided with a drum 16 partly inside the same and the chains are connected to these drums 16. The hubs 201 of drums 16 extend to the radial flanges of the complement wheels and have attached thereto springs 202 the outer ends of the springs being attached to the wheels and serving when the chains cause rotation of the drums 16 to compel the complement wheels to follow such rotation. In order to maintain the drums 16 and complement wheels in proper relative position, lugs 92 and 93 are provided, lugs 93 being carried on drums 16 and lugs 92 being carried on the complement wheels. As will be seen from Figs. 9 and 10 the springs 202 press the lugs 92 against the lugs 93 and when rotation of drums 16 is caused by the movement of the chains the complement wheels will follow the drums because of the springs 202. The complement wheels 95 15, 17, 19 and 21 as will be seen follow the movement of drums 16 in the reverse direction but may be moved independently thereof under control of the deposit mechanism.

Deposit mechanism.—The description of the deposit mechanism may be premised by stating that the downward movement of the operating lever 38 serves to release the main cover for the cash receptacles and until this is released the deposit mechanism is inaccessible to the operator. This main cover also serves after operation of the deposit mechanism to cause the ejection or delivery of the proper amount of change from the machine as the cover is returned to its normal position. Assuming therefore that the cover has been moved so that access may be had to the deposit mechanism, reference may be made particularly to Fig. 5. The cash receptacles which are shown in perspective in Fig. 24, 100 have separate covers thereover preventing any deposited coins from being inserted into the receptacles until the separate covers are moved. These covers are indicated by numeral 29 (Figs. 5 and 12) and are 105 provided with depending projections 30 actuating 110

racks 25 operating on ratchets 28 rigidly connected to the complement wheels 15, 17, 19 and 21. The projections 30 are so positioned as to cause a differential rotation of the complement wheels when the covers 5 are moved rearwardly to deposit coins. A cash receptacle and corresponding cover 29 will be provided for each denomination of coins intended to be used with the machine and there will be a corresponding projection 30 for each of said varieties of coins. Each of the 10 complement wheels however is provided with only one rack 25 and in order that more than one cover 29 and projection 30 may act thereon the racks 25 are pivoted to levers 26 which are journaled on shaft 27, said levers 26 being provided with a laterally extending projection 15 99 against which the depending projections 30 are adapted to engage. In the case of the dimes selecting wheel 17 it is clear that the ten cent, twenty five cent and fifty cent covers 29 should engage therewith, the ten cent cover moving the rack 25 one step and the fifty 20 cent cover moving the rack five steps. This is provided for by the difference of extent of the depending projections 30 as indicated in Fig. 13 whereby more or less lost motion is given to the rack 25. It will be evident that in the case of the twenty-five cent cover 29 25 this should produce two increments or units of motion of the dimes selecting wheels 17 and five increments of movement of the penny selecting wheel 15. This latter movement of the penny wheel 15 may be effected by having the 25-cent cover actuate the penny selecting wheel five spaces, or the 25-cent cover may simply actuate the dimes selecting wheel two spaces and then the operator may manually actuate the 5-cent cover to move the penny selecting wheel the necessary five spaces.

35 A corresponding description of the one dollar, two dollar and five dollar covers might be given, but it is thought that the mechanism will be clearly understood without such additional description. When the rack-bars 25 are moved as above described, the ratchets 28 40 serve to cause a positive movement of the complement wheels and this will clearly be allowed, inasmuch as the lugs 92 of the complement wheels may be moved away from the lugs 93 of the drums 16, the only result being the tensioning of springs 202. By this means the 45 complement selecting wheels 15, 17, 19 and 21 are positively set in accordance with the amount of the deposit and are therefore clearly in position such that the amount of change desired is indicated by the numbers on the said wheels. To take a specific case, suppose a 50 five dollar bill is tendered in payment of a sale amounting to forty-three cents. When the purchase keys P representing forty-three cents, that is, key 3 in the first bank from the right and key 4 in the second bank are depressed and the yoke piece Y lowered, the complement 55 wheels are reversely moved, the units wheels being reversed three steps so that the numeral 7 is shown, the dimes selecting wheel 17 being reversed 4 steps so that the numeral 6 is shown. It being remembered that the operation of any of the pawls 1, 2, 3 and 4 serve 60 to cause movement of the fingers 5, 6 and 7 so that their planes of movement intersect the chains, it will be seen that each of the fingers 5, 6 and 7 will cause one reverse step of movement of the complement selecting wheels 17, 19 and 21. The complement wheel 17 will 65 be moved one additional reverse step so that 5 is indi-

cated and the complement wheels 19 and 21 will each be moved one reverse step so that each indicates 9. The complete indication on the complement selecting wheels is therefore 9957. When the five dollar cover 29 is operated the complement wheel 19 will be moved 70 in a positive direction five steps thereby causing it to indicate 4. The complement selecting wheels 15 and 17 will remain in their previous position but the complement wheel 21 will be moved positively one step by the transfer mechanism not yet described in detail, to 75 restore the zero indication originally showing thereon. The entire indication then will be 0457 and it is clear that this is the proper amount of change for the transaction.

To provide a transfer operating in a positive direction on the complement selecting wheels the mechanism in Figs. 1, 9 and 31 may be employed. Directly over the complement selecting mechanism is a shaft 40 provided with three pairs of pinions mounted on sleeves on the said shaft, the sleeves being separated by 80 collars. One pinion of each pair is wider than the other and the shaft as a whole is adapted to be slid laterally in its bearings in the frame. The wide pinion 41 is connected through the sleeve with pinion 46, the wide pinion 43 with pinion 47 and the wide pinion 45 with 85 pinion 48. The wide pinions 41, 43 and 45 at all times mesh with gears G carried by the complement change selecting wheels 17, 19 and 21. On the wheels 15, 17 and 19 are mounted yielding ratchets 52 (see Fig. 9) which are, in the normal position of the mechanism, 90 adapted to pass the narrow pinions 46, 47 and 48 without operating them, but when shaft 40 is slid in its bearings toward the left, the said narrow pinions are in the path of the yielding ratchets so that when the positive movement of the complement change selecting wheels 95 100 is given by the covers 29 the ratchets 52 will engage the pinions at the proper time and actuate the same an extent sufficient to cause a movement of the next higher complement wheel through one step. As shown in Fig. 31 the shaft 40 is normally pressed toward the left 105 by the spring 50. A spring 51 at the left hand end thereof is in the path of main operating lever 38 and therefore at the top of the stroke of said lever it engages the spring 51 and positively moves the shaft 40 toward the right, this withdrawing the narrow pinions 46, 47 and 48 from the paths of the yielding ratchets 52. As soon as the handle starts on its downward movement the shaft 40 is released and spring 50 will then cause the lateral movement of the same to bring the transfer mechanism into operation. At the end of the operation of the machine the handle 39 is again raised and thereby causes the lateral movement of the shaft 40 to the right again carrying the narrow pinions out of the path of the yielding ratchets.

It will be remembered that the complement selecting wheels are under the tension of the springs 202 at all times, and for this reason when the positive movement is given to the wheels through the rack bars 25, some means of preventing reverse rotation of said wheel is necessary. This mechanism may take many forms 125 but is shown herein as comprising a shaft 32 shown in Fig. 5 and in detail in Fig. 32 carrying a series of loose pawls 31 thereon and surrounded by a sleeve 33 having slots through which the pawls 31 pass. Springs 74 surround the sleeve 33 and are connected thereto at 130

one end and to one of the pawls 31 at the other end. The slots in the sleeve 33 are of sufficient extent to allow a limited movement of the pawls 31, though the springs 74 normally tend to force said pawls against one end of the slots. Rigidly attached to one end of the sleeve 33 is a crank arm 34 connected by a pin to a vertically moving rod 35 which is, near its opposite end provided with laterally extending pins 36 and 37. This vertical bar 35 is shown in Figs. 14 and 18 and it will be clear 10 from these figures that the lever 38 at opposite ends of its stroke engages the lateral pins 36 and 37 and first depresses and then elevates the bar 35. As was before stated the lever 38 is depressed to adjust the complement wheels to the position representing the complement 15 movement of the sale, and at the conclusion of the down-stroke of said lever it strikes the pin 36 and slightly depresses the bar 35, thereby rotating sleeve 33 and causing the pawls 31 to move under tension of springs 74 into the path of the teeth on ratchets 28. The positive 20 movement of the complement selecting wheels causes the teeth of ratchets 28 to pass under the pawls and, because of the separate springs 74 only the pawl corresponding to the moving complement wheel will be oscillated during this operation. The pawls clearly 25 prevent reverse movement of the complement wheels at this stage of the operation. At the end of the operation lever 38 is raised to its uppermost position and as it reaches such position it strikes pin 37 of the vertical bar 35 and elevates said bar, thereby reversely oscillating the sleeve 33 and carrying the pawls 31 away from the teeth of ratchets 28 so that the springs 202 and 203 in the complement wheels and their drums may reset 30 both the wheels and the drums to their normal zero position.

35 *Coin delivering mechanism.*—The operation of the mechanism as thus far described is complete as far as the change and sale indicating and sale registering is concerned. The complement wheels 15, 17, 19 and 21 and their operating mechanism have been completely 40 described and it will be clear that means for adjusting them in opposite directions differentially has been explained. The mechanism for delivering or ejecting the proper change may now be described.

It will be remembered that some reference to the 45 main cover for the cash receptacles was previously made and it was stated that this cover was released at the down stroke of the operating lever 38 and that the closing of said cover controlled the delivery of change. In Fig. 14 as well as Fig. 34 the cover 66 is shown in 50 its closed position while in Fig. 18 the cover is shown in its open position and it may be noted that the position of the parts in Fig. 34 is intended to represent that period in the operation when the lever 38 has been depressed almost but not quite to its lowermost position. The cover 66 is provided with two rearwardly 55 extending bars one of which bearing reference numeral 65 is shown in Fig. 28, and the other of which bearing reference numeral 81 is shown in Figs. 14 and 21. The arm 31 is provided at its rearward end with a projection 60 adapted to engage the latch 80 pivoted to the main frame of the machine, and bearing a pin 83 which is adapted as indicated in Fig. 18 to be struck and depressed by the operating lever 38 as it reaches its lowest position. When the lever reaches this position the 65 latch 80 is tripped allowing the main cover 66 to open.

Mounted on a cross rod 60 is a frame shown in perspective in Fig. 11 comprising vertical arms 59 connected by cross rods a' and 61, each of the arms 59 being provided at its forward end with a pin 62 normally directly under the arms 65 and 81 of the cover 66. The frame bars 59 are provided with lateral camming projections 63 and fastened to the bars are pivoted pawls 64 the relative positions and shape of which are best shown in Fig. 11. At the rear ends of arms 65 and 81 pins 87 are provided which in the opening movement of the cover 66 elevate and pass by the pivoted latches 64, but on the closing movement of cover 66 the pins 87 are prevented from passing between the projections 63 and the latches 64 and thereby rock the frame arms 59 rearwardly although in their further rearward movement the arms 65 and 81 finally engage pins 62 on the frame arms 59 and reset the frame to its normal position. It will be seen that no movement of the frame arms is caused by the opening of the cover 66 but that on the closing of the same, first a downward rotation and then a forward rotation of the frame arms 59 around their pivot rod 60 is given.

Journalized on sleeves 58 on the rod a' are lever arms 23 and 24 one for each of the cash receptacles from which it is desired to eject change. As will be clear 90 from Figs. 5 and 12 the upper arms 23 of the levers are normally directly forward of the several complement wheels and at their lower ends are connected for movement with bars 57 connected to the ejecting slides 68. Each of the complement wheels is provided with 95 differentially graded projections (shown as pins) which are adapted to be engaged by and stop the arms 23 of the said vertical levers, when the rod a' is moved rearward during the first part of the closing of the cover 66. A development of the units complement wheel 15 is 100 shown in Fig. 13 to exhibit clearly the differential arrangement of the ejector controlling pins. It will be evident that on opposite ends of a diameter of the complement wheels the indications there found will differ by five units so that if for instance zero is exhibited at 105 the top of the wheel the figure 5 will be at the bottom thereof. If any of the pins are in the path of the arms 23 of the vertical levers, it will be evident that when the rearward movement of bar a' is given the levers will be rocked around their lower ends as fulcrums, thereby 110 carrying the upper ends 23 rearward until they strike and are stopped by the graduated pins. During the remainder of the rearward movement of bar a' the pins act as a fulcrum for the levers, thereby compelling a rearward movement of the lower ends thereof, which 115 rearward movement will clearly carry the bars 57 and slides 68 rearward also. This rearward movement will be sufficient to carry the slides 68 from under the cash receptacles so that the coins therein may drop enough to carry the lowermost coin into the path of slides 68. 120 When, during the latter part of the closing movement of cover 66, the frame 59 is given its forward rotation, the bar a' will consequently be moved forward also and the levers 23, 24 will again rock around their lower ends as fulcrums until they abut the rod 27, when this 125 will become the fulcrum for the levers, and the further forward movement of rod a' will cause a forward movement of the lower ends 24 of the levers, thereby causing an equal forward movement of the ejecting slides 58 with a consequent ejection of the proper coins. 130

The above description contemplates the ejection of one coin only from any of the receptacles and if this is desired to be used the placing of the graduated pins on the complement wheels is a simple matter. It will be remembered that the indication showing above any of the complement wheels and the figure at the bottom of said wheel are five units apart. Attention may be called to the diagram of Fig. 13. This figure shows the units complement wheel 15 which is adapted to control the nickel and penny receptacles. There are shown two lines of projections on this figure, the left hand line indicating projections for controlling the nickel receptacle and the right hand line the projections for the penny receptacle. It will be seen that opposite the indications 5, 6, 7, 8 and 9 no pin for the nickel receptacle is shown whereas opposite the zero, 1, 2, 3 and 4 indications pins are shown. It will be clear that when the number 5 for example is exhibited at the top of the indicator the pin opposite the zero will be at the lowest point thereof and will serve to stop the proper lever 23 and 24 as before described and cause the ejection of a nickel in change. This clearly also applies to the pins opposite numbers 1, 2, 3 and 4 which would respectively be in position to cause the ejection of a nickel when the indicator showed 6, 7, 8 and 9. On the other hand when the numbers 0, 1, 2, 3 and 4 are exhibited at the upper side of the selecting wheel 15 no nickel coin should be ejected and consequently no pins are found opposite the respective numbers 5, 6, 7, 8 and 9. A similar description of the complement wheels of higher order might be given but it will, it is thought, be clear how the pins thereon are to be arranged. It may be here noted that as the machine is shown no provision for ejecting twenty five cent pieces is made so that if for example forty cents was to be ejected it would be given out in the shape of four ten cent coins instead of one twenty five cent, one ten cent and one five cent coin.

In order to provide for the ejection of more than one coin at a time from any desired receptacles, use is made of the principle of differential positioning of the projecting pins. It will be remembered that the pins controlling the nickel receptacle are all directly opposite the indications on the complement wheel but it will be seen from Figs. 12 and 13 that the penny receptacle controlling pins are not so positioned. As a premise to the description of the manner of placing these pins attention may be first called to Figs. 22 and 23. The cash receptacles indicated in these figures by reference numeral 55 are surrounded by sleeves 54 arranged to be elevated or depressed in accordance with the number of coins to be ejected. Mounted on the slides 57 and riding in a longitudinally inclined slot therein are ejecting devices 56 provided with depending flanges at the rear end thereof adapted to engage the bar r' of a frame piece F supporting all the ejectors. At the forward end thereof the slides 57 are provided with an inclined ratchet composed of four teeth as it will never be necessary to eject more than four coins of any one denomination at an operation. Connected by pins to the inclined ejectors are pawl devices 67 having depending teeth adapted to engage the inclined ratchet teeth.

It will be evident that when the ejecting slides 57 are drawn rearwardly by the levers 23, 24 the depend-

ing flanges 69 will finally engage and be stopped by the frame bars. During any further rearward movement of the slides 57 the pawl devices 67 will be forced up the inclined ratchets thereby gradually elevating the ejecting bars. This furnishes a very simple means for determining how many coins shall be ejected from any given receptacle in as much as all that is necessary in order to produce this differential elevating of the ejecting slides is to provide for different extents of rearward movement of the slides 57 after the flanges 69 have engaged the frame bars r' . This differential movement of the slides 57 is caused by the differential positioning of the pins on the complement wheels. It will be obvious that with the principle of operation of this ejecting mechanism the amount of rearward movement of slides 57 depends on the position in which the upper ends of the levers 23 and 24 are stopped. The rod a' has a constant movement at each operation so that if the upper ends 23 of the vertical levers are stopped at an early part of the movement, the lower ends 24 of the levers will have a greater extent of movement and vice versa. In other words the movement of the upper and lower ends 23 and 24 of these levers may in a sense be said to be complementary. It will be seen from Fig. 13 that opposite the numbers 0 and 5 of the complement selecting wheel no pins are shown in the penny line and clearly none are necessary inasmuch as the numbers 0 and 5 indicate that no pennies are required. Opposite the figures 6 and 1 pins J and C are shown in the penny line and this is evidently necessary to cause the ejection of one cent. Opposite the figures 7 and 2 the pins are slightly above the horizontal line passing through the nickel controlling pins and it will be clear from Fig. 12 that this position of the penny pin serves to stop the upper ends of the vertical levers in a position slightly forward of that in which they would be stopped by the pin opposite the number 6. This will evidently allow an additional step of rearward movement of the penny slide 57 thereby causing the pawl device 67 to be elevated over one tooth of the inclined ratchet and there-through elevating the penny ejector so that two pennies will be ejected by the forward movement of the slide. Opposite the numbers 8 and 3 on the complement wheel the penny pins are still further in advance of the nickel pins than was the case with the penny pins opposite 7 and 2 and it will be evident, following the previous reasoning, that the upper ends of levers 23-24 will be stopped slightly sooner than was the case in the previous instance, thereby allowing a further additional movement of the slides 57 and an additional elevation of the ejectors 56, so that finally three pennies would be ejected from the penny receptacle. It will be evident from the position of pins opposite the numerals 9 and 4 on the complement wheel that four pennies will be ejected from the receptacle 55. The object of the sleeve 54 is to prevent accidental disengagement of the coins from the receptacles. This sleeve is at all times supported by the ejector slide as shown in Fig. 22, although Fig. 23 indicates the position of the mechanism when the coins have been ejected but before the sleeve had time to drop. As the forward movement of the slides 57 is given, the proper number of coins are ejected and the pawl device 67 finally engages the sleeve 54. Any further forward movement of the slide 57 disengages

the pawl 67 from the inclined ratchet causing it to assume the position of Fig. 23 so that during the further forward movement of the slide 57 the inclined ejector remains stationary as far as the forward movement is concerned, though it is gradually depressed due to the inclined slot in which it moves.

In some cases paper money may be desired to be used and to accommodate this type of currency I provide small receptacles shown in Figs. 16, 17, 19, 20 and 21 each adapted to hold a bill and to be placed in the coin tubes. Any other desired shape of bill holders may be used.

After the ejection of the change the mechanism should be returned to normal position and in order to allow this it is necessary to raise the lever 38 which serves to control the sale indicators and the selecting mechanism. As the lever 38 reaches its upper position the pawls 31 will withdraw from the teeth of ratchets 28 as before explained and the springs 202 and 203 then reset both the drums 16 and the complement selecting wheels 15, 17, 19 and 21 to their respective normal positions, the chains 8, 9, 10 and 11 being at the same time rewound around drums 16 thereby elevating the slides 8. The elevation of the slides 8 will clearly allow their contained springs to reset the sale indicators to zero position as far as the mechanism described is concerned at least. It is because of the timing of this resetting operation that both the yielding ratchets 52 and the sliding shaft 40 are provided. Inasmuch as the ratchet 52 is to transfer in a positive direction the normal position of the ratchets must be immediately adjacent the transfer pinions. When the lever 38 starts to move downwardly the complement wheels will be reversely rotated and the ratchets 52 will be moved past the pinions 46, 47 and 48. It will be remembered that the lateral shift of shaft 40 to the left occurs immediately after the lever 38 starts to move so that in most cases the pinions 46 and 47 and 48 would be shifted into the path of the yielding ratchets before the ratchets have passed them, but in this case the ratchets will yield and pass by without moving the pinions. When the complement selecting wheels are moved in a positive direction the transfer should take place provided any of the ratchets pass from the nine to the zero position and in this direction of movement the ratchets will not yield but will operate the pinions. So far therefore the shaft 40 might have remained at its left position without detriment to the operation, but at the resetting period of the operation the complement wheels may be moved in either direction toward their zero position depending on how they had been previously moved, and although when moving in the negative directions the ratchets 52 do not reach the point occupied by the transfer pinions yet when moving in an opposite direction the ratchets 52 would pass the pinions and if they had not been previously shifted to their right hand position would actuate the same, thereby displacing the next higher complement wheel. It is for this reason that the shaft 40 is made slideable and the ratchets 52 are made yielding.

It is desirable to prevent the sale indicators from being viewed during the operation of the machine as thereby a completion of the operation is secured and to this end there is provided a flash or curtain 76 which as shown in Fig. 14 normally covers and prevents exhibition of the sale indicators. This flash 76 is carried by

arms 75 which are mounted for forward movement on the machine frame, the movement being caused by the forwardly extending levers 77 connected to the bars 75 through pins 79 and provided at their forward ends with lateral pins 78 adapted to be engaged by the lever 38 as it reaches its lowest position and operated so as to raise the flash 76. This position of the mechanism is shown in Fig. 18. When the lever 38 is restored to its upper position the weight of the flash 76 and arms 75 together with a spring if necessary restores the flash to its lower concealing position.

In order to compel a complete stroke of the operating lever 38 mechanism shown in Figs. 28, 29 and 30 may be employed. Mounted on the machine frame is a track 98 having projecting ends 91 between which the yoke arms Y move and mounted on said yoke arms are quadrant pieces 89 provided with notches 96 and 97 in each of which a pin 90 projecting from the yoke arm Y and spring pressed as shown in Fig. 29 may enter. The arc of the quadrant 89 is slightly flattened so that the center of the arc is slightly nearer the pivot 99 than are the ends of the arc. With this construction it will be seen that when the parts are in the position of Fig. 28 no obstruction to the upward rotation of yoke arms Y will be caused by the quadrant 89 but that if attempt is made to reverse the movement and move the yoke arms Y downwardly the quadrant will jam against the track 98 and prevent such movement. When the yoke arm Y reaches its uppermost position the edge of the quadrant will engage the upper projection 91 of the track 98 and shift the quadrant until the notch 97 engages the pin 90 when the yoke arm Y may be moved downwardly without obstruction by the quadrant 89. This mechanism though simple is very effective to compel a complete operation in each movement of the yoke arm Y and consequently a complete movement of the operating parts of the machine.

The register used in connection with this invention needs only a brief description, as it is precisely the same as that employed in the patent previously referred to. The register comprises a series of disks B carried on the shaft which supports the sale-indicating drums, and is connected to said drums by a ratchet and pawl connection or some other type of mechanism so as to move differentially with the indicating drums in one direction only. As the mechanism is described in the patent, the operation of the register takes place with the setting movement of the indicating drums, and not with the movement of restoration.

Details of the purchase key-board are shown in Figs. 6 and 7, from which figures it will be seen that the keys P are carried by inner and outer segmental frame-pieces p and p' serving to both support and guide them. The keys have each a cut-away portion forming upper and lower shoulders, and against these cut-away portions rest springs 70 carried in ribs p² of the frame-piece p'. It will be clear that the springs 70 prevent excessive movement of the keys P in either direction. The yoke-piece Y carries a cam device for positively pushing the keys to their outward position after they have performed their function of laterally moving the operating pawls 1, 2, 3 and 4.

It is thought that the operation of the mechanism will be clear from the foregoing description, but it may be briefly recapitulated as follows, and it will be assumed

that \$2.75, comprising two silver dollars, a half dollar and a quarter, have been tendered in payment of a purchase amounting to \$2.51.

The purchase amount, namely, \$2.51, is first set up 5 on the purchase key-board by depressing the key marked "1" in the cents row, the key marked "5" in the dimes row, and the key marked "2" in the dollars row. When the operating handle 38 is moved downwardly from the position of Fig. 14 to that of Fig. 18, 10 the yoke Y carrying the operating pawls 1, 2, 3 and 4 is given a complete downward movement, and after this movement has been half completed the pawl 2 engages the proper notches in the dimes slide s, so that during the further movement of the yoke-piece Y the 15 said dimes slide is carried therewith. The lateral movement of pawl 2 when it strikes the depressed dimes key, results in shifting the fingers 6 and 7 laterally through the interlocking slides 13 and 12, but pawls 3 and 4 are left in their inoperative position. When 20 the yoke-piece Y reaches the key marked "2" in the dollars bank, the pawl 3 is moved laterally to engage the dollars slide s', and carries the said slide with it through the remaining steps of movement. Next the cents pawl 1 strikes the depressed units key marked 1, 25 and is cammed laterally to engage the last tooth of the units slide s in order to give the said slide one increment of movement. As the pawl is moved laterally the slide 14 which is pinned therewith is also moved, thereby carrying the finger 5 to the position shown in Fig. 1. 30 This lateral motion of pawl 1 would carry the fingers 6 and 7 with it, but they have already been operated through the pawl 2. As the slides s move downwardly they carry the chains 8, 9 and 10, and thereby rotate the complement selecting wheels 15, 17 and 19 by rotating the corresponding drums 16, and thereby tending to tension the springs 202. When the yoke-piece Y reaches the last step of its movement, the fingers 5, 6 and 7 engage the chains 9, 10 and 11 and move them enough to give the complement wheels 17 and 19 an additional step of movement and to move the complement wheel 21 one step. As a result of this part of the 40 operation, the complement indicating wheels show 9749 at the indicating points thereof, and the change selecting devices have now been set in correspondence with the purchase amount. As the slides move downwardly they rotate the indicating drums 1 to an amount dependent on the amount on the slides, so that the said drums exhibit the purchase amount, namely, \$2.51, at their indicating point and an equal 50 amount is registered on the registering disks B.

As the lever 38 reaches the lower end of its stroke, it strikes the pin 83 on the latch 80, and trips the same, thereby releasing the amount cover 66, which immediately opens. At this same time the flash or shutter 76 is raised to exhibit the purchase amount on the indicating wheels through the levers 77 connected to said flash, and also operated by the lever 38. The slide 35 is depressed through its pin 36 when the lever 38 strikes the same, thereby throwing the retaining pawls 31 into 60 position to engage the ratchets 28 of the complement selecting wheels to prevent their rearward movement. As the amount cover 66 moves open the pin 87 passes between the projection 63 and the pawl 64 on the ejector frame arms 59 without moving the same.

65 The deposit amount is now to be entered in the

machine, and this is done by sliding rearward the covers 29 for the proper receptacles and dropping the money received into the said receptacles. In the present case the one-dollar cover 29 will be operated twice in succession, thereby moving the complement wheel 19 two steps in advance. The 50-cent cover 29 will be moved rearward once, thereby rotating the complement wheel 17 five steps, and the 25-cent cover 29 will be moved rearward once, thereby giving two additional steps of movement to the complement wheel 19, 75 and five steps to the complement wheel 17. After the one-dollar cover 29 has been moved rearward twice, the complement wheels will show 9949. After the 50-cent cover has been moved rearwardly, they will indicate 9999, and finally after the 25-cent cover has been moved, the said wheels will show 0024. This last number is clearly the amount of change which should be received, being the difference between the amount paid in and the amount of purchase. When the one-dollar cover and the 50-cent cover 29 are moved rearwardly, the proper complement wheels only are advanced, but when movement of the 25-cent cover is given the transfer mechanism, comprising the pinions 45 and 48, will be engaged and moved by the yielding latch 52 of the complement wheel 15, thereby giving 85 the complement wheel 17 an additional step of movement. This transfer also takes place between the wheels 17 and 19 and 19 and 21, thereby causing each of the higher wheels to be advanced one extra step. 90

To eject the proper change the cover 66 is operated 95 to its closed position. As the arms 65 and 81 rock rearwardly, the pins engage the latch 64 on the frame arms 59 and rock the frame rearward about its pivot 60, and finally the arms 65 and 81 themselves engage the pins 62 and restore the frame 59 to its normal position. As 100 the frame rocks rearwardly the upper ends 23 of the ejector-controlling levers will be moved around their lower ends 24 as a fulcrum until the dimes lever 23 strikes the proper pin on the complement selecting wheel 17, and the pennies lever 23 strikes the proper pin on the 105 complement selecting wheel 15. These two levers will then be retained at their upper ends, and the further rearward movement of shaft a' will move the dimes and the pennies ejectors rearwardly. In both of the cases in point the ejectors are arranged to eject from 110 one to four coins at a time, and it will clearly be necessary in the present supposed case to eject two dimes and four pennies. When the dimes ejector moves rearwardly, the flange 69 of the inclined slide is engaged by the frame-piece 7', and then during the continued rearward movement of the ejectors the dimes slide 56 is elevated, so that the pawl 67 thereof rides over two teeth of the inclined ratchet and the penny ejector is moved rearwardly to the position of Fig. 22, which is such a position as to eject four pennies. When 120 the frame 59 is rocked forwardly around its pivot, the shaft a' causes the levers 23-24 to move until the parts 23 engage the rod 27, when they are stopped and the ejecting slides then moved forward to eject the proper change. 125

The operation is now complete, except to reset the parts, and this is done by raising the handle 39 to its upper position. During the last part of this movement the slide 35 is raised, thereby withdrawing the pawls 31 from the ratchets 28 of the complement selecting 130

wheels, and their springs, together with the springs of the corresponding drums 16, will reset the selecting mechanism to normal position, also raising the slides *s* to their normal position. The transfer shaft 40 is finally 5 moved to the right in Fig. 1, thereby withdrawing the narrow pinions 46, 47 and 49 from the path of the yielding ratchets 52.

It will be noticed that although the purchase keys are adapted to indicate any amount less than \$100, 10 that the deposit mechanism is only arranged to provide for \$10, as the highest single coin or bill deposited. In case it was desired to change the highest amounts, it would be necessary to provide additional covers 29, one for the \$20 coins or bills, and one for \$50 bills. The 15 principle of operation would, however, be precisely the same as applied to the mechanism as shown. Furthermore, it is clearly possible to operate the covers 29 and their corresponding racks a plurality of times, producing an additional movement of the complement selecting wheels, the only limit to this operation 20 being a complete rotation of the complement wheels in question.

I have shown the controlling mechanism as comprising purchase keys, but it will be clearly understood 25 that other forms of controlling mechanism well known in the art may be substituted therefor. For example, a well-known type of machine is provided with adjustable levers movable over a scale corresponding with amounts of purchase, and this could clearly be 30 used to move the slides *s* of the present mechanism. So, too, many substitutes may be devised for the cover 66 which controls the ejection of change. It is clear 35 that a crank-handle or lever would be an equivalent, broadly, of this cover, as far at least as its function of causing the movement of the ejecting mechanism is concerned.

The selecting mechanism herein shown has been referred to in the specification as "complement wheels" 40 and "complement-selecting mechanism," and possibly other terms, but it will be understood that these terms are not limitations of the function of this device, any mechanism which is adapted to be adjusted or positioned or controlled in opposite senses or directions by the purchase and deposit mechanism being intended 45 to be included within the scope of the invention and to be described by the term "selecting mechanism." So, too, the various specific devices utilized herein for accomplishing the broad purposes set forth, may be replaced by other forms of mechanism without departing 50 from the broad spirit of the invention.

I believe that I am the first in the art to devise a machine of the character described which will automatically compute and deliver the amount of change represented by the difference between any amount of 55 deposit and any amount of purchase. Prior to this invention there existed machines for merely delivering change; that is, if any certain amount of change were desired, value keys to that amount would be operated and the machine would eject that amount of 60 change. But such prior machines required some form of mental calculating on the part of the operator to secure the proper change, and no prior machine was suitable for or capable of use as a real automatic change-maker for handling the commercial transactions involved.

ing the making of the proper change for the great variety of deposit amounts and purchase amounts.

In my invention, the manipulative amount determining means are such that they may be operated according to any amount of deposit and any amount of purchase, and the machine automatically computes 70 and controls the change ejected from the machine, thus entirely dispensing with any form of mental calculation with its ensuing errors. These manipulative means control the intermediate change controlling or selecting mechanism, which in turn controls the money 75 delivery or ejecting devices, and I wish to claim this generic invention in its broadest aspect, regardless of the form of the said manipulative means, or of the selecting means, or of the ejecting means. The manipulative means need not necessarily be in separate 80 groups for the deposit and the purchase amounts, but if so, their respective order of operation is immaterial in so far as concerns the broad scope of the invention; and the change controlling or selecting mechanism may assume various forms, being controlled in one 85 sense or in one direction by the deposit mechanism and in another sense or in another direction by the purchase mechanism, or may be put into one condition under the control of the deposit mechanism, and into another condition under the control of the purchase 90 mechanism, the resultant or final position or condition controlling and determining the ejection of the proper amount of change. Likewise, many of the devices which I have shown and described herein as forming parts of the entire mechanism for accomplishing the 95 above described results, are broadly new in themselves separately considered and as such entitle the claims thereon to a broad scope. Therefore it may be stated that while the form of mechanism here shown and described is admirably adapted to fulfil the objects primarily stated, it is to be understood that it is not intended to confine the invention to the one form of embodiment herein disclosed, for it is susceptible of embodiment in various forms all coming within the 100 scope of the claims which follow.

What is claimed is as follows.

1. In a cash indicating machine, the combination of a sale indicator, a change indicator and co-operating mechanism for actuating said indicators, substantially as set forth.

105

2. In a cash indicating machine, the combination with a sale indicator mechanism, of a change maker, and co-operating mechanism for controlling the sale indicator mechanism and the selective change distributive action of the change maker, substantially as described.

110

3. In a cash indicating machine, the combination of a sale indicator, a change indicator, a change maker and co-operating mechanism for actuating said sale and change indicators and said change maker, substantially as set forth.

115

4. In a cash registering machine, the combination of a sale register, a change indicator and co-operating mechanism for actuating said register and said indicator, substantially as set forth.

120

5. In a cash registering machine, the combination of a sale register, a change maker and co-operating mechanism for actuating said register and change maker, substantially as set forth.

125

6. In a cash registering machine, the combination of a sale register, a change indicator, a change maker and co-operating mechanism for operating said register, indicator, and change maker, substantially as set forth.

130

7. In a cash indicating and registering machine, the combination of a sale indicator, a sale register, a change indicator and coöperating mechanism for operating said indicators and registers, substantially as set forth. 85
- 5 8. In a cash indicating and registering machine, the combination of a sale indicator, a sale register, a change maker, and coöperating mechanism for actuating said indicator, register and change maker, substantially as set forth. 90
- 10 9. In a cash indicating and registering machine, the combination of a sale indicator, a sale register, a change indicator, a change maker and coöperating mechanism for actuating the same, substantially as set forth. 95
- 15 10. The combination with a change indicating device of means for operating the same corresponding to the amount of a sale, and means for reversely operating the same corresponding to the amount presented in payment whereby the final position of said device indicates the amount of change, substantially as set forth. 100
- 20 11. The combination with a rotary change indicating device, of means for operating the same corresponding to the amount of a sale, and means for reversely operating the same corresponding to the amount presented in payment whereby the final position of said device indicates the amount of change, substantially as set forth. 105
- 25 12. The combination in a change selecting apparatus, of a device for indicating the complement of a sale, means for operating said device, means for reversely operating said device to indicate the amount presented in payment, whereby the final position of said device determines the amount of change to be ejected, and means for ejecting the same, substantially as set forth. 110
- 30 13. The combination in a change selecting apparatus, of a rotary device for indicating the complement of the amount of the sale, means for operating said device, and means for reversely operating said device to indicate the amount presented in payment, whereby the final position of said rotary device determines the amount of change to be ejected, and means for ejecting the change, substantially as set forth. 115
- 35 40 14. In a machine for making change, the combination of receptacles or tubes, boxes for carrying paper money or coins of various denominations and arranged to securely hold the same without the aid of a movable cover and adapted to be inserted in said receptacles or tubes, and expelling devices for expelling such boxes from the receptacles or tubes, substantially as set forth. 120
- 45 50 15. In a cash indicating machine, the combination with a sale indicator, of a change indicator, predetermining means operating according to the amount of the sale and independent means operated according to the amount received whereby the change indicator is made to indicate the difference between the amount of the sale and the amount received. 125
- 55 60 16. In a cash indicating machine, the combination with a change indicator, of two instrumentalities coöperating with the change indicator to determine its position according to the amount of the sale and the amount received and a change making device controlled by the change indicator, whereby change is delivered according to the amount shown on the indicator. 130
- 65 70 17. In a cash register, the combination with a register, of a change maker, predetermining means operated according to the amount of the sale and other predetermining means operated according to the amount received, and devices connecting both of said means to the change maker whereby the amount of the sale is registered and the difference between the amount of the sale and the amount received is discharged from the change maker. 135
- 75 80 18. In a change maker, the combination with a movable element, of means for actuating the same according to the amount of the purchase, means for further actuating the same according to the amount received to bring it to a position representing the difference between the two amounts, and a money changer controlled by said movable element. 140
- 85 19. In a change indicating machine, the combination with a change indicator, of means for giving same two position movements at each operation according to purchase and deposit amounts, and manipulative devices controlling said movements. 145
- 5 20. In a change indicating machine, the combination with a change indicator, of means for moving same differentially in opposite directions successively, and manipulative devices controlling said movements. 150
21. A change making mechanism including a rotary coin selecting device coöperating with means to move the same an amount corresponding to the amount of the sale and reversely an amount corresponding to the amount offered in payment, the final position of said device determining the amount of change to be distributed. 155
22. In a change making machine, the combination with a change selecting mechanism, of means for adjusting same differentially for an amount of change, change delivering mechanism controlled by said selecting mechanism, and means for actuating said delivering mechanism. 160
23. In a change making machine, the combination with a change selecting mechanism, of manipulative devices controlling the operation of said selecting mechanism, in one sense, additional manipulative devices controlling the operation of said selecting mechanism in an opposite sense, and ejecting mechanism controlled by said selecting mechanism. 165
24. In a change making machine, the combination with a change selecting mechanism, of manipulative devices controlling the movement of same in one direction, additional manipulative devices controlling the movement of said selecting mechanism in an opposite direction, ejecting mechanism controlled by said selecting mechanism and means for operating said ejecting mechanism. 170
25. In a change making machine, the combination with change delivering mechanism, of rotary selecting devices controlling same, means for adjusting said devices in opposite directions, the final position determining the amount of change, and transfer mechanism between the separate selecting devices. 175
26. In a change making machine, the combination with change delivering mechanism, of selecting devices controlling the operation of said mechanism, separate mechanisms for adjusting said devices successively in opposite directions, the final position determining the amount of change, and devices whereby the selecting devices operate those of higher orders at intervals. 180
27. In machine of the class described, the combination with change delivering devices, of selecting mechanism for controlling same, comprising rotary devices movable separately in two directions, said devices provided with change determining elements placed in graduated positions. 185
28. In a machine of the class described, the combination with change delivering mechanism, of means controlling the operation of same, said means comprising selecting devices movable separately in opposite directions and provided with projections placed in graduated positions. 190
29. In a machine of the class described, the combination with change delivering mechanism, of selecting means controlling the delivery of change by same, said means comprising selecting devices movable separately in opposite directions and provided with differentially placed operating elements. 195
30. In a machine of the class described, the combination with change delivering mechanism, of selecting means controlling the delivery of change by same, said means comprising rotary devices movable separately in opposite directions, and provided with graduated surfaces which determine the operation of the delivering mechanism. 200
31. In a machine of the class described, the combination with change delivering mechanism, of devices for operating same, selecting means controlling the operation of said delivering mechanism, manipulative means for positioning said selecting means in one sense, and additional means for positioning said selecting means in an opposite sense. 205
32. In a machine of the class described, the combination with change delivering mechanism, of selecting means controlling the operation of same, manipulative means positioning said selecting means in one sense and keys for positioning said selecting means in an opposite sense, the final position determining the amount of change. 210
33. In a machine of the class described, the combination with change delivering mechanism, of devices for deter- 160

mining the amount of change delivered, and deposit and purchase mechanisms for controlling said devices.

34. In a machine of the class described, the combination with a change delivering mechanism, of deposit manipulative devices and purchase keys, and controlling devices for said change delivering mechanism acting under control of said manipulative devices and purchase keys.

35. In a machine of the class described, the combination with a combined change indicator and selector, of means for adjusting same successively in opposite senses, and change delivering devices controlled from said selector in its final condition.

36. In a machine of the class described, the combination with a cash indicator, and means for adjusting same for a purchase amount, a change selector set in one sense by said adjusting means, means for reversely setting said selector, in accordance with a deposit amount, and change delivering mechanism controlled by said selector.

37. In a machine of the class described, the combination with a combined change indicator and change selecting mechanism, of manipulative devices and purchase keys controlling the adjustment of same in opposite directions, and change delivery mechanism controlled by said selecting mechanism for delivering the amount of change exhibited on said indicator.

38. In a change making cash register, the combination with a cash changing mechanism controlled in part according to coins inserted, of a registering mechanism and means for operating the registering mechanism and controlling the cash changing mechanism.

39. In a change making cash register, the combination with change making and ejecting mechanism, mechanism operated in accordance with the coins inserted for controlling the operation of the change making and ejecting mechanism, registering mechanism for the amounts of sales, and means engaging with and adapted to operate the change making and ejecting mechanism and the registering mechanism.

40. In a machine of the character described, mechanism adapted to receive cash of a greater value than a sale, a change making and ejecting mechanism adapted when operated to deliver an amount of cash equal to the difference between the value of the sale and the cash inserted in the receiving mechanism, means for regulating the operation of the change making and ejecting mechanism and adapted to cause the change making and ejecting mechanism to deliver an amount of cash between the sale and the value of the cash inserted in the receiving mechanism, means for operating said ejecting mechanism, a controlling mechanism for the said operating mechanism, means for operating the said regulating and controlling mechanisms, and a receiving means for the cash ejected.

41. In a change making cash register, the combination with a change making and ejecting mechanism adapted when operated to eject the change between the value of a sale and the value of the amount tendered in payment, mechanism controlled according to the coins inserted for controlling the operation of said change making and ejecting mechanism, a registering mechanism for registering the value of a sale, and means operatively connected with said mechanisms for operating the same.

42. In a change making machine, the combination with a change making and ejecting mechanism, means for controlling same in accordance with the amount inserted in the machine, a series of purchase amount determining devices, means controlled by said devices for also controlling the change making and ejecting mechanism and means for operating the ejecting devices to eject change from the machine.

70 43. In a change making cash register, the combination with a change making and ejecting mechanism, means for controlling same in accordance with the amount inserted in the machine, a series of purchase amount determining devices, purchase amount indicating devices controlled by said determining devices, means controlled by said devices for also controlling the change making and ejecting mechanism and means for operating the ejecting devices to eject change from the machine.

44. In a change making cash register, the combination with a change making and ejecting mechanism, means for

controlling same in accordance with the amount inserted in the machine, a series of purchase amount determining devices, purchase amount registering devices controlled by said determining devices, means controlled by said devices for also controlling the change making and ejecting mechanism and means for operating the ejecting devices to eject change from the machine.

45. In a change making cash register, the combination with a change making and ejecting mechanism, means for controlling same in accordance with the amount inserted in the machine, a series of purchase amount determining devices, indicating and registering devices for said purchase amounts controlled by said determining devices, means controlled by said devices for also controlling the change making and ejecting mechanism, and means for operating the ejecting devices to eject change from the machine.

46. In a change making machine, the combination with a change making and ejecting mechanism, of means controlling said change making mechanism in accordance with amounts inserted in the machine, means controlling same in accordance with the amount of purchase and means for operating said ejecting mechanism to eject amounts from the machine.

47. In a change making machine, the combination with a change making and ejecting mechanism comprising a series of receptacles for different denominational amounts, means for controlling said mechanism selectively according to the amount of purchase and to the amount tendered in payment and means for selectively actuating said ejecting mechanism to eject from the proper receptacles the difference between the two amounts.

48. The combination of a slide and means for moving it, an indicating wheel actuated by said slide, a complement wheel also actuated by said slide, and means for giving said complement wheel an independent movement in the reverse direction, substantially as described.

49. In a cash register and change making device, the combination of two or more slides and mechanism for moving them, complement wheels in number equal to said slides, swinging hangers actuated by mechanism connected with slides of a lower order and adapted to coact with slides of a higher order to produce additional movements of the complement wheel of the higher order.

50. In a cash register, the combination with indicating wheels, the slides, pawl and yokes substantially as described for moving said wheels, one or more movable fingers and sliding connections between the said fingers and pawls operating to change the position of the ends of said fingers and to throw them into position or out of position to actuate the complement wheels, substantially as described.

51. In a cash register, and change making machine, the combination of indicating wheels, slides operating to move said indicating wheels, and a yoke and pawls adapted to actuate said slides, fingers adapted to actuate the change mechanism, said fingers being attached to said yoke and actuated by means of slides connected with said pawls, and a stop adapted to swing said fingers from the actuating position, substantially as and for the purpose described.

52. In a change maker, the combination of sale indicators, complement indicators coacting with said sale indicators, independent actuators for said complement indicators, coin expelling mechanism and actuators therefor, the expelling movement of said coin expelling mechanism being determined by the position given to said complement wheels by their several actuators, substantially as and for the purpose specified.

53. In a change making cash register, the combination of the keys P, the yoke Y, the pawls and slides, the change indicating drums and flexible connections between the slides and drums, and fingers arranged to be moved into or out of position, to bear against the flexible connection, substantially as and for the purpose described.

54. In a cash register, a series of wheels bearing numbers on their peripheries, which numbers are employed for the purpose of indicating any desired number, impelling slides equal in number to said wheels, flexible connections between said slides and said wheels, and fingers

movable into a position to engage with said flexible connections, and arranged as described to bend said flexible connection out of its course and thereby to cause in said wheel a motion additional to that caused by the movement 5 of said slide, substantially as and for the purpose described.

55. In a cash register and change making machine, the combination of an indicating wheel, a drum, a slide arranged to rotate both the indicating wheel and drum, a 10 spring arranged to return said drum to normal position against said slide, and a complement wheel containing a spring and arranged to follow the motion of said drum through the force of its own spring, but capable of motion in the reverse direction, substantially as described.

15 56. In a cash register and change making device, the combination of two or more slides and mechanism for moving them, complement wheels equal in number to said slides, swinging hangers actuated by mechanism connected with slides of a low order and adapted to connect 20 with slides of a higher order to produce additional movements of the complement wheel of the higher order.

25 57. The combination of main indicating wheels, complement wheels, means adapted to set the complement wheels to indicate a number complementary to that indicated on the main wheels, a secondary actuator adapted to actuate the complement wheels to a new position indicating the addition of an amount to the number previously indicated thereon, the complement wheels and the second actuator being disengaged during the period of actuation 30 of the said wheels by the first actuator, substantially as described.

35 58. In a cash register, in combination with indicating wheels, the slides, pawls and yoke substantially as described for said wheels, one or more movable fingers and sliding connections between said fingers and said pawls operating to change the position of the ends of said fingers and to throw them into position or out of position to actuate the complement wheels, substantially as described.

40 59. In a cash register and change making machine, the combination of indicating wheels, slides operating to move said indicating wheels, and a yoke and pawls adapted to actuate said slides, fingers adapted to actuate the change mechanism, said fingers being attached to said yoke and actuated by means of slides connected with said pawls, 45 and a stop adapted to swing said fingers from the actuating position, substantially as and for the purpose described.

50 60. In a cash register and change making machine, the combination of main indicating wheels, complement wheels actuated in one direction simultaneously therewith, sliding actuating racks adapted to engage the complement wheels and rotate them independent of the main indicating wheels in a direction reverse to the motion first given them, substantially as described.

55 61. In the complement wheel of a change making device, the combination of a rotating drum actuated in unison with the indicating wheels, a follower drum, a spring adapted to actuate the follower drum, and means adapted to give to the follower drum a reverse rotary movement 60 independent of the first drum, substantially as and for the purpose specified.

62. In combination with the complement wheel, a ratchet wheel and rack arm extending to and operated by a slide representing a denomination of money, a stop 65 limiting the actuating motion of said rack arm, and a pawl arranged to hold said ratchet wheel, all combined and operating as described.

63. In combination with the complement wheel, a ratchet wheel and rack arm, and means for actuating said 70 rack arm, a holding pawl arranged to be normally out of contact with said ratchet wheel, and means adapted to move said pawl into holding contact therewith, substantially as and for the purpose described.

64. In combination with a complement wheel provided 75 with pins or stops, a coin receptacle, a slide adapted to expel coin from said receptacle, and a lever mounted on a movable fulcrum and adapted to engage with said expelling slides, and with said pins or stops on the complement wheel, substantially as and for the purpose specified.

80 65. In combination with complement wheels, provided

with stops arranged around the periphery, coin receptacles and coin expelling slides, a rocking bar, levers supported on said rocking bar having one end engaged with said coin expelling slides and one end adapted to engage with and be stopped by a stop on said wheel, whereby the actuating 85 movement of the slide engaging end of said lever is determined by the location of the stop engaging the opposite end of said lever, substantially as and for the purpose described.

66. The combination of a coin holder having an opening 90 through which one or more coins may be expelled, a variable expelling device for expelling one or more coins, means for automatically adjusting said expelling device according to the number of coins desired, and mechanism for operating the same. 95

67. The combination of a coin holder having an opening through which one or more coins may be expelled, a device on said holder for varying the size of said opening according to the number of coins to be expelled, means for automatically operating said device, a variable expelling device for expelling one or more coins, means for adjusting said expelling device according to the number of coins desired, and mechanism for operating the same. 100

68. In combination with a coin tube arranged to hold coins and deliver them from the bottom, a compound expelling slide arranged to move across the bottom of said coin tube and to vary its thickness in proportion to its travel backward before making its return or expelling movement. 105

69. In combination with a coin tube arranged to hold 110 coins and deliver them from the bottom, a variable expelling slide arranged as described to increase in height in proportion as it is drawn backward preparatory to expelling coins from said tube, and to assume its normal thickness after the expulsion of coins, substantially as and for 115 the purpose described.

70. The combination of a coin holder having an opening through which one or more coins may be expelled, and a device on said holder for varying the size of the opening according to the number of coins to be expelled, and means for expelling the desired number of coins arranged to automatically adjust the device for varying the size of the opening in the opening in the tube. 120

71. The combination of a tube arranged to hold coins and deliver them from the bottom through an opening 125 which will permit the passage of several coins, and a device movable on said tube and closing down over the opening through which coins are expelled, whereby the size of said opening can be varied to permit the passage of only a single coin or of several coins, and means for expelling 130 the desired number of coins arranged to automatically adjust the device for varying the size of the opening in the tube.

72. In combination with a tube arranged to hold coins and deliver them through an opening from the bottom which will permit the passage of several coins, a sleeve movable on said tube and closing down over the opening through which coins are expelled, whereby the size of 135 said opening can be varied to permit the passage of only a single coin or of several coins.

73. In combination with a coin tube arranged to hold coins and deliver them through a slide opening at the bottom, a sleeve movable with respect to said tube whereby the size of said opening may be varied, and an expelling 140 slide of variable thickness operating as described to vary the delivery opening for the expulsion of one or several coins. 145

74. In a change maker, a change selector containing movable parts having independent motion, and connected together so that, when one part has moved so as to represent an amount of money equal to that represented by one unit of motion of the next part, the second part will be moved one such unit. 150

75. In a change maker, a change selector containing 155 movable parts having independent motion, and connected together so that, when one part has moved so as to represent an amount equal to that represented by one unit of motion of the next part, the second part will be moved one such unit, said parts being disks or wheels mounted in gangs. 160

76. In a machine of the character described, the combination of a series of independent money receptacles for different denominations of money, a series of change selecting mechanisms, means for carrying from one change selecting mechanism to another of higher denomination, means for setting the change selecting mechanisms to agree with a sum of money received, means for resetting such change mechanisms to an extent equivalent to the amount of a purchase, and means enabling the removal 10 from the machine of an amount equal to the difference between the said two amounts. 85
77. In a machine of the character described, the combination of selecting cylinders, notched selecting disks thereon, independent pinions controlling the several cylinders, carrying mechanism operatively connecting one cylinder with another, operating racks, engaging said pinions, controlling levers operating said racks, purchase levers also operatively connected to said pinions to revolve them in an opposite direction to that in which they are revolved by said racks, and ejecting mechanism controlled by said selecting disks, substantially as described. 90
78. In a change maker, the combination with a change making mechanism including expelling devices, of a cash safe having a movable member for permitting access to the money, and means controlled by said movable member for operating said expelling devices. 105
79. In a change maker, the combination with a change making mechanism including expelling devices, of a money receptacle having a movable lid to permit access to the money in the receptacle, and means controlled by the movement of said lid for operating said expelling devices. 110
80. In a change maker, the combination with a series of coin holding receptacles, of movable members coöperating with the coin inserting openings to said receptacles, a series of accounting elements, and means controlled by said movable members to give differential movements to said accounting elements according to whichever member is moved. 115
81. In a change maker, the combination with a series of 40 coin holding receptacles, of movable members coöperating with the coin inserting openings of said receptacles, and a change making mechanism including means controlled by said movable members for controlling the amount of change. 120
82. In a change maker, the combination with a series of coin holding receptacles having movable members coöperating with the coin inserting openings of said receptacles, a change making mechanism including a series of coin expelling devices and selective controllers therefor, and means coöperating with said movable members for actuating a plurality of said controllers for said coin expelling devices. 125
83. In a change maker, the combination with a series of amount keys, of a change indicator controlled by the 55 amount keys and storage receptacles for the change provided with movable members also controlling the change indicator. 130
84. In a change maker, the combination with a change indicator, of means for moving said indicator according to the amount of the sale, and a series of money receptacles having movable members also connected to the change indicators for moving the same according to the amount received. 135
85. The combination with a series of coin receptacles 65 having movable covers, of a series of indicators connected to said covers and moved thereby when the cover is actuated to permit coins to be placed in the receptacle. 140
86. In a machine for making change, the combination of receptacles or tubes, and a circular receptacle for carrying 70 money, said receptacle having top and bottom walls and a permanent opening through which the money is inserted, and which receptacle is adapted for insertion in the said receptacles or tubes, substantially as and for the purpose set forth. 145
87. In a machine for making change, the combination of receptacles or tubes, boxes for carrying paper money or 75 coins of various denominations and having provisions for securely holding the same without the aid of a movable cover and adapted to be inserted in said receptacles or tubes, and expelling devices for expelling such boxes from the receptacles or tubes substantially as set forth. 150
88. In a machine for making change, the combination of storage receptacles, ejecting devices for said receptacles and a series of open ended receptacles arranged to be placed in the storage receptacles with coin or bills therein so that they may be ejected from the storage receptacles at will. 155
89. In a machine for making change, the combination of a series of storage receptacles, a series of open ended coin or bill receptacles arranged to be placed in said storage receptacles, and means for ejecting the desired number of coin or bill receptacles from the storage receptacles. 90
90. In combination with wheels provided with stops, coin holding tubes arranged to deliver coins from their bottom, expelling slides, and a compound lever consisting of one part held centrally to a movable fulcrum, said fulcrum forming part of a swinging frame, pivoted to a fixed framework, and said swinging frame being provided with two lugs, an arm hinged to the framework and adapted to engage consecutively with said lugs and produce consecutive motions in opposite directions of the said movable fulcrum, substantially as and for the purpose described. 100
91. The combination of the levers 23, 24, the rocking fulcrum support 59, the stop 63, the hinged stop 64, the door 66 acting as a lever, the arm 65 and the pin 87 arranged to, engage with the stops 63, 64 as the door 66 closes, and to pass between them as the door opens, substantially as and for the purpose described. 105
92. The combination of the framework, a yoke and yoke arm, a main actuating lever, a hanger 89 provided with notches 96, 97, a spring actuated pin 90, an arched track 91 provided, with stops at either end adapted to engage the hanger, substantially as described. 110
93. The combination with the main actuating lever, a hanger connected to said lever, and a curved track concentric to the center around which said levers turn, stops at the end of said curved track, the said hanger having its surface of contact with the said track curved with a radius greater than the distance from its point of suspension to the said curved track whereby the said hanger tends to jam between the said track and its suspending pivot. 115
94. In a change making machine, the combination with change delivery mechanism, of a selecting device differentially adjustable and controlling said change delivery mechanism, and actuating means for said delivery mechanism. 120
95. In a change making cash register, the combination with change delivery mechanism, of a rotary selecting device controlling said delivery mechanism, and actuating means for said delivery mechanism. 125
96. In a change making cash register, the combination with change delivery mechanism, of a rotary selecting device differentially adjustable and controlling said mechanism, and actuating means for said delivery mechanism. 130
97. In a change making cash register, the combination with change delivery mechanism and means for actuating the same, of a selecting device for controlling said mechanism and means for adjusting said selecting device. 135
98. In a change making cash register, the combination with change delivery mechanism and actuating devices for the same, means for controlling said delivery mechanism, and mechanism for differentially positioning said means. 140
99. In a change making cash register, the combination with change delivery mechanism and actuating devices for same, of rotary means for controlling said delivery mechanism, and means for differentially rotating said controlling means. 145
100. In a change making cash register, the combination with two sets of manipulative devices representing desired amounts, of difference computing mechanism controlled by both sets and automatically adjusted to the difference in amounts exhibited by the sets of manipulative devices. 150
101. In a change making cash register, the combination with two sets of manipulative devices adjustable in correspondence with desired amounts, of subtracting mechanism, and operating means for automatically adjusting said mechanism to positions representing the difference between amounts exhibited by the sets of manipulative devices. 155
102. In a change making cash register, the combination with a change indicator, of two sets of manipulative de- 160

- 5 vices representing amounts and an operating mechanism for moving said indicator differentially to position to exhibit the difference between the amounts exhibited on said sets of manipulative devices.
- 5 103. In a change maker, the combination with a change controlling device, of means for actuating said device according to the amount of the purchase, means for also actuating the same according to the amount received whereby the resultant position of the device represents the 10 difference between said two amounts; and money delivering devices controlled by said change controlling device.
104. In a change maker, the combination of a change controlling device, manipulative means operable according to the amount paid in and the amount of purchase, connections between said manipulative means and said change controlling device to cause the latter device to assume a 15 condition for controlling the amount of change equal to the difference between the amount paid in and the amount of purchase; and money delivering devices controlled by 20 said change controlling device.
105. In a change indicating device, the combination of a change indicator, manipulative means operable according to the amount paid in and the amount of purchase; and connections between said manipulative means and said 25 change indicating device to cause the latter device to assume a position representing the amount of change equivalent to the difference between the amount paid in and the amount of purchase.
106. In a change making device, the combination with 30 money delivering devices, of manipulative means operable according to the amount paid in and the amount of purchase, and connecting means between said manipulative means and said money delivering devices for automatically determining the proper change equivalent to the difference between the amount paid in and the amount purchased.
107. In a change making device, the combination with 35 money delivering devices, of a series of manipulative devices operable according to the amount paid in, a second series of manipulative devices operable according to the amount purchased, and connections between said manipulative devices and money delivering devices for automatically determining the amount of change to be delivered equivalent to the difference between the amount paid in 40 and the amount purchased.
108. In a change indicating machine, the combination with a change indicator comprising denominational elements separately movable in adding and subtracting directions, of means controlling the movement of said elements in accordance with amounts of purchase, and means for moving each element of higher denomination in a subtracting direction when the element of next lower denomination passes from normal zero position in a subtracting direction.
- 55 109. In a change indicating machine, the combination with a change indicator comprising denominational elements separately movable in adding and subtracting directions, of means for causing movements of said elements in accordance with amounts of purchase, and mechanism for 60 causing an independent movement of any element of higher denomination when the element of next lower denomina-
- tion leaves its normal zero position under control of said means.
110. In a change making machine, the combination with a change delivering mechanism, of denominational selecting devices for controlling said delivering mechanism, denominational manipulative devices for causing movement of said selecting devices in accordance with amounts of purchase, and means caused to operate by the manipulative devices of lower denominations for changing the condition of selecting devices of higher denominations so as to cause delivery of less change of the higher denominations than would be delivered if the manipulative devices remained unoperated.
111. In a change making machine, the combination with a change delivery mechanism, of denominational change selecting devices controlling said change delivery mechanism, denominational manipulative devices for adjusting said selecting devices in accordance with purchase amounts, and means controlled by the manipulative devices of lower denominations for giving an adjustment of the selecting devices of higher denominations independently of their adjustment under control of the manipulative devices of higher denominations.
112. In a change selecting mechanism, the combination with a change delivering mechanism, of denominational change selecting mechanism controlling said delivering mechanism, denominational manipulative devices for determining the position of said selecting mechanism, and means controlled by the manipulative devices of lower denominations for co-operating in the determination of the position of the selecting devices of higher denominations.
113. In a change making machine, the combination with a change delivering mechanism, of denominational change selecting mechanism for controlling said delivery mechanism, denominational manipulative devices for controlling said selecting mechanism and means rendered operative by the manipulative devices of lower denominations for independently controlling the selecting mechanism of higher denominations to an extent of one unit of value thereof.
114. In a change making machine, the combination with a change delivering mechanism, of denominational change selecting mechanism controlling said delivering mechanism, denominational manipulative devices for controlling said selecting mechanism, and transfer devices between the elements of said selecting mechanism.
115. In a change making machine, the combination with a change delivering mechanism, of change selecting mechanism comprising a plurality of separately adjustable elements for controlling said delivering mechanism, means for determining the positions of said selecting elements according to amounts of purchase, and devices for automatically transferring movement from one said element to the next element.

In testimony whereof, I sign this specification in the presence of two witnesses.

FRANCIS Q. OSBORN.
